UNITED STATES PATENT OFFICE.

FREDERICK W. MARTIN, OF BROOKLYN, NEW YORK, ASSIGNOR TO FRANKLIN RAILWAY SUPPLY COMPANY, A CORPORATION OF DELAWARE.

LUBRICATOR.

Application filed October 12, 1923. Serial No. 668,049.

My invention relates to lubricators for axle boxes, particularly the driving boxes of locomotives. I aim to facilitate the packing of such axle lubricators with grease and 5 their insertion in the axle box, and to insure proper operating adjustment of the lubricator after insertion. The embodiment of my invention here illustrated and described 10 resembles somewhat the device shown in U. S. Patent No. 1,423,502 to Mitchell, granted July 18, 1922, and since assigned to the assignee of this application. However, my invention presents valuable distinctive features 15 of its own, as will hereinafter appear.

In the drawings, Fig. 1 is a side view of a driving box and lubricator embodying my invention, as seen from the inner side of the box, i. e., the side away from the corresponding driver.

Fig. 2 shows a vertical axial section 20 through the box and various associated parts, taken as indicated by the line 2—2 in Fig 1.

Fig. 3 is a plan view of a spreader with 25 which the driving box shown in Figs. 1 and 2 is provided.

Fig. 4 is a perspective view of the lubricator proper or "cellar" shown in Figs. 1 and 2.

The driving box 5 shown in Figs. 1 and 2 30 is in the main of standard type and construction. Between its sides or legs 6 is mounted a spreader 7, held in place by pins 8 extending through apertured lugs 9 on the legs 6 at either side of the axle 10 and similar 35 lugs 11 at the bottom of the spreader. As shown, the headed pins 8 are secured by cotter pins 12 through their inner ends. The lubricator 15 has the usual "cellar" form: it rests on the spreader 7 with a loose fit in the box 5, so that it can be slid in and out readily. It is provided with the usual formanious or perforated cover 16, and with the usual grease cake follower plate 17. This 40 follower 17 is urged upward by a helical compression spring 18 centered about a boss 19 on the cellar bottom, so as to press the grease through the cover 16 against the axle 10, and is provided with an indicator rod 20 and a pull chain 21 extending down through openings in the cellar bottom and in the spreader 7. As shown in Figs. 1, 2, and 3, the opening 20^a that accommodates the indicator 45 50 55 60 65 70 75 80 85 90 95 100 105 110 115 120 125 130 135 140 145 150 155 160 165 170 175 180 185 190 195 200 205 be inserted or removed with its follower 17 depressed as in Figs. 1, 2, or 4. Stop means to limit the endwise movement of the cellar 15 when inserted, and prevent it from sliding through the box 5, may advantageously have 60 the form of a lug 15^a on the inner end of the cellar 15. As shown in Figs. 1 and 3, the inner edge of the spreader 7 has a recess 7^a over the outer end of the slot 20^a, to accommodate the downward projecting lug 15^a. 65 The indicator 20 shows at a glance how much grease is left in the cellar 15 at any time, and when refilling or "packing" is necessary. When the cellar 15 is removed from the box 5, rod 20 and chain 21 afford a convenient 70 means of drawing down the follower 17 for repacking. Normally, the cellar 15 is retained in the box 5 by a securing member in the form of a rod or holding pin 22 extending 75 across the inner end of the box, through apertured lugs 23 at either side. In the present instance, these lugs 23 are attached to the spreader 7 (Fig. 3) rather than to the box sides 6. The holding pin 22 engages in a half-round seat 24 outstanding from the 80 end of the cellar 15. Inasmuch as the cellar 15 must generally be inserted in the box 5 with a new grease 85 cake, it is desirable to provide for relieving the correspondingly heavy follower tension due to the spring 18 when the cellar is being inserted. As here shown, this is accomplished by holding down the follower 17. For this purpose, one or more rods or pins 25 (Fig. 4) can be inserted through holes 26 in the ends of the cellar 15 above the follower 17 when drawn down (as shown in Fig. 4) after removal of the cellar 15 from the box 5, as described above, and removal of the cover 16 and the old grease cake. 90 With the follower 17 thus held down, a fresh grease cake of the form shown in Fig. 1 may be placed in the cellar 15 over the pins 2

other words, the rod 22 and the pins 25 have an interlocking relation that insures against the pins 25 being carelessly left in place and rendering the lubricator inoperative. Only 5 after the pins 25 have both been withdrawn, and the grease-feeding tension thus reestablished by release of the follower 17, can the member 22 be properly applied.

I claim:

- 10 1. The combination with an axle box, its lubricating cellar, and the follower plate of the latter, of means for securing the cellar in the box, and means for removing the follower tension from the axle for insertion of the cellar in the box, said means being 15 adapted to interfere with said securing means, so that the cellar cannot be secured until the tension has been established on the axle.
- 20 2. The combination with an axle box, its lubricating cellar, and the follower plate of the latter, of a securing member adapted to extend across the box to retain the cellar therein, and means for temporarily holding down the follower for insertion of the cellar in the box positioned to block the insertion of the securing means until said means are removed and the follower is released.
- 25 3. The combination with an axle box and apertured lugs at one end thereof, and a lubricating cellar with its follower plate,

of a holding pin for the cellar extending through said lugs, and one or more pins for holding down the follower for insertion of the cellar in the box protruding from the latter in the way of said holding pin, so as to prevent insertion of the latter in both lugs until the follower holding pins are themselves removed.

4. An axle box structure comprising a 40 spreader member, a cellar member, a follower plate in the cellar, follower retaining means, and cellar retaining means, said follower retaining means extending into the path of the cellar retaining means whereby 45 to prevent application of the cellar retaining means when the follower retaining means is in place.

5. The combination with an axle box, its 50 lubricating cellar, and the follower plate of the latter, of a spreader for the box carrying securing means for holding the cellar in the box, and means for removing the follower tension from the axle for insertion of the cellar in the box, said means being adapted 55 to interfere with said securing means, so that the cellar cannot be secured until the tension has been established on the axle.

In testimony whereof, I have hereunto signed my name.

FREDERICK W. MARTIN.
